UNITED STATES PATENT OFFICE.

CHARLES W. BREMKEN, OF CHICAGO, ILLINOIS, ASSIGNOR TO LAUNCELOT A. HARKNESS, OF CHICAGO, ILLINOIS.

VESTIBULE-CAR PLATFORM.

No. 845,750.

Specification of Letters Patent.

Patented March 5, 1907.

Application filed February 15, 1906. Serial No. 301,130.

To all whom it may concern:

Be it known that I, CHARLES W. BREMKEN, a citizen of the United States, and a resident of Chicago, in the county of Cook and State 5 of Illinois, have invented certain new and useful Improvements in Vestibule-Car Platforms, of which the following is a specification.

My invention is concerned with a novel construction for an automatically-raised 10 trap-door, constituting the extension of the platform of a vestibule-car, which door is down and in a horizontal position when under way, so as to make an unbroken surface in the vestibule-flooring, but which is raised to 15 a vertical position at the stops of the train to permit the passengers to descend by the steps which are located directly beneath it when it is down. Somewhat similar devices have heretofore been proposed for the same 20 purpose; but so far as I am aware all of them have been unsatisfactory in some point, and none of them has gone into general use.

My invention consists in certain novel features of construction and combinations 25 of elements which will first be described generally in the specification and the novel combinations then pointed out in the claims.

To illustrate my invention, I annex hereto 30 three sheets of drawings in which the same reference characters are used to designate 35 identical parts in all the figures of the drawings, of which—

Figure 1 is a vertical transverse section through the end of the car, as on the line 35 A A of Fig. 2. Fig. 2 is a horizontal section on the line B B of Fig. 1, but on an enlarged scale. Fig. 3 is a vertical section on the line C C of Fig. 2. Fig. 4 is a perspective view 40 of the hinge mechanism for the trap-door with the parts partially disassembled. Fig. 5 is a detail view of the latch mechanism in section on the line D D of Fig. 6. Fig. 6 is an end elevation of the latch mechanism. Fig. 7 is a front elevation of the operating- 45 handle on an enlarged scale, and Fig. 8 is a sectional view of the same on the line E E of Fig. 7.

The stationary portion 10 of the vestibule-platform, the steps 11, the vestibule-frame-work, and the exit-doors 12 are of the customary construction, and the general construction and operation of the trap-door 13 is the same as in the ordinary vestibule-car—that is to say, when the door 12 is closed, as ap- 55 pears in Fig. 2, the trap-door 13 is closed

down and serves to prevent the door 12 from being opened or any exit from the car. When a stop is made, the trap-door 13 being raised to a vertical position, the door 12 can then be swung inward and opened to permit the descent of the passengers upon the steps 11.

The trap-door 13 instead of being mounted upon ordinary hinges is mounted as best shown in Figs. 2 and 4, where it will be seen 65 that the pivoted end has secured thereon the generally U-shaped metallic cover 14, extending along that side and secured thereto, as best shown in Fig. 3. This casing 14 has secured in the ends thereof the bearing-collars 70 15, through which pass the hinge-rod 16, which is journaled in the bearing-brackets 17 and 18, suitably secured to the framework of the car, as indicated in Fig. 2. The hinge-rod 16 has secured thereon, preferably near 75 the center thereof, the collar or sleeve 19, which may be considered as consisting of two and preferably three sections, the central section 20 being in the form of a disk having the recesses 21 therein located at suitable 80 intervals, so that by the application of a key the rod can be turned, and this section 20 is exposed through the recesses 22 cut in the casing 14. The other section or sections 23 of the sleeve or collar 19 has the lug 24 projecting therefrom, of suitable shape to receive and hold the end 25 of the helically-coiled 85 torsion-spring 26, which is coiled about the rod 16, and has its other end 27 extending beneath the edge of the door 13 between it 90 and the bottom portion of the casing 14, the door being preferably recessed to permit of the end 27 of the spring entering it. While one spring might be employed, I preferably employ two, as shown, in order that the lifting 95 force may be applied more advantageously than if a single spring were employed. At the outer end of the rod 16 in a suitable recess 28, formed in the woodwork of the car, I secure the ratchet-disk 29, and I pivotally 100 mount upon the same side of the bracket 18 the detent-pawl 30, whose nose engages the ratchet-wheel 29, being spring-pressed into engagement therewith by the leaf-spring 31, secured to the adjacent flange of the bracket 105 18. If the lifting force of the spring becomes too weak, the train conductor or anybody in charge of the car by inserting a key in one of the recesses 21 will advance the ratchet-disk 29 a notch or notches, thereby increasing the 110

tension of the spring sufficiently to furnish the additional lifting power required. If by accident the tension should be made too great, the dog 30 can be withdrawn from engagement with the ratchet-wheel 29 by inserting a hook-shaped key through the aperture 32 in the narrower flange of the bracket 18 and into the recesses 33 in the body of the dog itself, so as to catch the dog by the hook 10 on the key and pull it out of engagement with the teeth of the disk 29. This flange is exposed when the door 12 is swung open, as will be readily seen by reference to Fig. 2.

By the hinging and spring mechanism here shown I have produced a trap-door that in appearance does not differ from the ordinary construction and in which the lifting force of the spring can be regulated as accurately as may be desired to throw the door to a vertical position when it is released from the latch, which must of course be employed to hold it in its horizontal position.

In the opposite side of the door 13 and preferably at its center I secure the keeper 34, having the recess therein with which the latch-bolt 35 co-operates. This latch-bolt is mounted to slide in suitable bearings formed in the latch-casing 36, which is secured in the sill adjacent the edge of the door. The inner 30 end 37 of the bolt is preferably reduced and of a circular shape, as shown, so that it will slide in the bearing-aperture 38 and confine the helically-coiled expanding-spring 39 between the casing and the shoulder 40 on the dog. The bolt has a recess 41 therein, into which extends the arm 42 of the three-armed lever or dog 43, which is pivoted upon the bearing-rod 44 in the latch-casing 36. The arm 45 has pivoted thereto the link 46, connecting it to the latch-operating mechanism to be described, and the other arm 47 is provided with a bearing-surface 48 so shaped, and located as to contact with the edge of the under side of the door 13 as soon or substantially as soon as it has been released from the latch 35, so as to positively start the door upward if by chance it should be stuck so as to not respond at once to the lifting action of the springs 26. The upper edge of the bolt 40 is of course beveled off, so as to be automatically moved back by the action of the keeper 34 as the door 13 is swung down to catch it and hold it automatically.

One feature of importance in my invention is the location of the operating-handle 49, by which the latch is operated. Heretofore the latch has been operated by foot near the door, producing a dangerous structure, as the foot of the operator was apt to be struck by 60 the door, or else the operating-handle has been located in a position where it was liable to be struck and operated accidentally by the passengers. In my improved construction this handle 49 is located, preferably, upon the 65 pilaster 50 at such a height that it is not pos-

sible to be struck by the bodies of the passengers, but it has to be operated by reaching upward, so that there is no chance of its being operated accidentally or by children or other curious individuals. The details of construction of this handle are best shown in Figs. 7 and 8, where it will be seen that the handle normally hangs in the vertical position shown and is secured upon the squared rod 51 and is journaled by the bearing portion 52 in the 70 bearing formed in the disk 53, which has an offset portion 54 thereof seated in the framework, while the body portion is secured thereto, as by the screws 55. The rod 41 passes through the squared aperture in the hub 56, 80 which carries the arm 57, to which is secured, as by the link 58, the end of the link-rod 59, which extends downward through the tube 60, which is embedded in the woodwork of the car, where it will be out of sight and yet 85 furnish an uninterrupted passage and guide-way for the link 59. The bearing or hub 56 is journaled in the bearing-bracket 61, which is secured to the interior woodwork by the screws, as shown, and is preferably provided 90 with the pin 62, which co-operates with the offset 63 on the hub 56 to hold the handle and associated mechanism in their proper position by the gravity of the parts. Of course the reason for separating the arm 57 from the handle 49 is to enable it to accommodate itself readily to constructions in which the width of the open space in the woodwork varies.

The link 59, extending down through the 95 tube 60, finally emerges from the bottom of the car and is connected to one arm of the bell-crank lever 64, which is pivoted upon the bearing-bracket 65, secured to the bottom of the car in front of the steps 11. A link 66 connects the bell-crank 64 with a corresponding bell-crank 67, pivoted upon a similar bearing-bracket 68, and the link 46, attached to the dog 43, is of course secured to the other arm of the bell-crank 67, so that by swinging 110 the handle 49 slightly from its vertical position the latch 35 will be withdrawn and the trap-door released and fly upward under the impetus of the spring.

If desired, a buffer may be secured to the 115 end of the car-body proper in position to cushion the final opening movement of the trap-door.

It will be noticed that the bell-cranks for releasing the latch are outside the car adjacent the steps, where those familiar with that construction and mode of operation can operate them from the outside, and thus obtain access to the car, if necessary, under emergency conditions, which sometimes arise, as if a passenger has been shut out prior to the starting of the car or is on the closed side and does not have time to reach the other side before the train pulls out.

The operation of the apparatus will be 130

readily apparent, and it will be understood that while I have shown and described my invention as embodied in the form which I at present consider best adapted to carry out its purposes it is capable of modifications and that I do not desire to be limited in the interpretation of the following claims, except as may be necessitated by the state of the prior art.

10. What I claim as new, and desire to secure by Letters Patent of the United States, is—

15. 1. In a device of the class described, the combination with the car-body having the vestibule-platform, the steps, and the trap-door pivotally secured to the car-body so as to cover or expose the steps as desired, of means coöperating with the trap-door to raise it automatically, a latch for holding it down, a releasing-handle for the latch located 20 and exposed only at a point high enough to prevent its being accidentally operated by contact with the body of an adult, and connections inaccessible from within the car between the handle and the latch.

25. 2. In a device of the class described, the combination with the car-body having the vestibule-platform, the steps, and the trap-door pivotally secured to the car-body so as to cover or expose the steps as desired, of 30 means coöperating with the trap-door to raise it automatically, a latch for holding it down, a releasing-handle for the latch located on the pilaster adjacent the exit to the next car and exposed only at a point high enough 35 to prevent its being accidentally operated by contact with the body of an adult, and connections inaccessible from within the car between the handle and the latch.

40. 3. In a device of the class described, the combination with the car-body having the vestibule-platform, the steps, and the trap-door pivotally secured to the car-body so as to cover or expose the steps as desired, of 45 means coöperating with the trap-door to raise it automatically, a latch for holding it down, a releasing-handle for the latch located at a point high enough to prevent its being accidentally operated by contact with the body of an adult, and connections between 50 the handle and the latch, consisting of the link connected to the handle and inclosed within the framework of the car and extending down to a point beneath the platform, the bell-crank lever to which it is connected, 55 a second bell-crank lever, a link connecting the two bell-cranks, and a third link connecting the second bell-crank and the latch.

4. In a device of the class described, the combination with the car-body having the 60 vestibule-platform, the steps, and the trap-door pivotally secured to the car-body so as to cover or expose the steps as desired, of means coöperating with the trap-door to raise it automatically, a latch for holding it 65 down, a releasing-handle for the latch located

at a point high enough to prevent its being accidentally operated by contact with the body of an adult, and connections between the handle and the latch, including a link inclosed within the frame of the car and extending down to the level of the latch.

5. In a device of the class described, the combination with the car-body having the vestibule-platform, the steps, and the trap-door pivotally secured to the car-body so as to cover or expose the steps as desired, of 70 means coöperating with the trap-door to raise it automatically, a latch for holding it down, a releasing-handle for the latch located at a point above the trap-door and projecting downward to the outside of the frame of the car, the arm connected to the handle and rotating therewith inside the frame of the car, and a link extending downward within the car and ultimately connected to the latch.

6. In a device of the class described, the combination with the car-body having the vestibule-platform, the steps, and the trap-door pivotally secured to the car-body so as to cover or expose the steps as desired, of 90 means coöperating with the trap-door to raise it automatically, a latch for holding it down, a releasing-handle for the latch extending downward and journaled to rotate upon a horizontal axis, a squared shaft carried by the handle, an arm having a square aperture through which the squared shaft passes within the framework of the car, and a link extending from the arm downward through the framework of the car and ultimately connected with the latch.

7. In a device of the class described, the combination with the car-body having the vestibule-platform, the steps, and the trap-door pivotally secured to the car-body so as 105 to cover or expose the steps as desired, of means coöperating with the trap-door to raise it automatically, a latch for holding it down, releasing means for the latch, and mechanism connected with said releasing 110 means for positively starting the door in its upward movement, consisting of a bell-crank rocked by the releasing means, one arm of which operates the latch and the other arm of which engages the under side of the door 115 adjacent the latch to lift it when the latch has been moved far enough to release it.

8. In a device of the class described, the combination with the car-body having the vestibule-platform, the steps, and the trap-door pivotally secured to the car-body so as to cover or expose the steps as desired, of 120 means coöperating with the trap-door to raise it automatically, a latch for holding it down, a releasing-handle for the latch, a three-armed bell-crank pivoted adjacent the latch, one arm of which engages and operates the latch and another arm of which engages the under side of the door adjacent the latch 125 to lift it when the latch has been moved far 130

enough to release the door, and connections between the third arm of the bell-crank and the releasing-handle.

9. In a device of the class described, the combination with the car-body having the vestibule-platform, the steps, and the trap-door pivotally secured to the car-body so as to cover or expose the steps as desired, of a helically-coiled torsion-spring located along the axis of the pivot of the door and acting directly thereon to raise it when it is released, a latch for holding the door down, a releasing-handle for the latch, connections between the handle and the latch, and means for adjusting the tension of the spring.

10. In a device of the class described, the combination with the car-body having the vestibule-platform, the steps, and the trap-door pivotally secured to the car-body so as to cover or expose the steps as desired, of a helically-coiled torsion-spring located along the axis of the pivot of the door and acting directly thereon to raise it when it is released, a latch for holding the door down, a releasing-handle for the latch, connections between the handle and the latch, and means for increasing the tension of the spring step by step, and means for releasing its tension entirely.

30 11. In a device of the class described, the combination with the car-body having the vestibule-platform, the steps, and the trap-door pivotally secured to the car-body so as to cover or expose the steps as desired, of the rod upon which the door is pivoted, the spring surrounding the rod and engaged thereby at one end, and by the door at the other end, the ratchet-disk on the rod, a dog coöperating therewith permitting its movement in one direction only, means for turning the rod, a latch for holding the door down, and releasing means for the latch.

45 12. In a device of the class described, the combination with the car-body having the vestibule-platform, the steps, and the trap-door pivotally secured to the car-body so as to cover or expose the steps as desired, of the rod upon which the door is pivoted, the collar located upon the rod provided with the peripheral apertures and a lug to engage the spring, the spring surrounding the rod and engaged by the lug at one end and by the door at the other, the ratchet-disk on the rod, a dog coöperating therewith permitting its movement in one direction only, means for turning the rod, a latch for holding the door down, and releasing means for the latch.

50 13. In a device of the class described, the combination with the car-body having the vestibule-platform, the steps, and the trap-door pivotally secured to the car-body so as to cover or expose the steps as desired, of the rod journaled in bearings secured to the car-body, the casing U-shaped in cross-section

forming the pivot side of the door, the spring 65 within the casing surrounding the rod and engaged by the rod at one end and by the door and casing at the other, a ratchet-disk on the rod, a dog coöperating therewith permitting its movement in one direction only, 70 means for turning the rod, a latch for holding the door down, and releasing means for the latch.

14. In a device of the class described, the combination with the car-body having the vestibule-platform, the steps, and the trap-door pivotally secured to the car-body so as to cover or expose the steps as desired, of the casing U-shaped in cross-section secured on and forming the pivot edge of the door, a rod 75 upon which the casing is pivoted, mounted in bearings carried by the car-body, the collar secured on the rod provided with the apertures and a lug to engage a spring, the spring surrounding the rod and engaged by the lug at one end and by the door and casing at the other end, the ratchet-disk on the rod, a dog coöperating therewith, 80 the portion of the collar carrying the apertures projecting through a recess in the casing, a latch for holding the door down, and releasing means for the latch. 85

15. In a device of the class described, the combination with the car-body having the vestibule-platform, the steps, and the trap-door pivotally secured to the car-body so as to cover or expose the steps as desired, of the rod upon which the door is pivoted, a collar provided with apertures and two lugs to engage ends of the springs on either side of the apertures, and adapted to be secured near the middle of the rod, the springs surrounding the rod and engaged by the lugs on the collar at one end and by the door at the other end, the ratchet-disk on the rod, a dog coöperating therewith, a latch for holding the door down, and releasing means for the latch. 90

16. In a device of the class described, the combination with the car-body having the vestibule-platform, the steps, and the trap-door pivotally secured to the car-body so as to cover or expose the steps as desired, of the rod upon which the door is pivoted, the spring surrounding the rod and engaged thereby at one end and by the door at the other end, the ratchet-disk upon the rod, a 100 dog coöperating therewith, having an aperture therein, means for turning the rod, an aperture in the casing adjacent the dog to give access thereto, a latch for holding the door down, and releasing means for the latch. 105

In witness whereof I have hereunto set my hand and affixed my seal this 7th day of February, 1906.

CHARLES W. BREMKEN. [L. S.]

In presence of—

L. A. HARKNESS,
L. E. WOODWARD.
